Frank R. Petronio, Pittsburgh, Pa.

Application April 30, 1954, Serial No. 30,280

Term of patent 7 years

(Cl. D48—20)

To all whom it may concern:

Be it known that I, Frank R. Petronio, have invented a new, original, and ornamental Design for a Lamp Base, of which the following is a specification, reference being had to the accompanying drawings, forming a part hereof.

I claim:

The ornamental design for a lamp base, as shown.
